[57] CLAIM

The ornamental design for an antenna pedestal, as shown and described.

DESCRIPTION

FIG. 1 is front elevational view of an antenna pedestal showing my new design; the back elevational view being the same;

FIG. 2 is top plan view thereof;

FIG. 3 is a bottom plan view thereof;

FIG. 4 is a right side elevational view thereof; the left side elevational view being the same; and,

FIG. 5 is a front elevational view of a further embodiment of the top section of the top section of the antenna pedestal, the remainder of this further embodiment being the same as shown in FIGS. 1-4.

FIG. 5

FIG. 4

FIG. 2

FIG. 3

FIG. 1
